UNITED STATES PATENT OFFICE.

JAMES A. HICKS AND FRANK H. HILL, OF ATLANTA, GEORGIA.

FLUID-PRESSURE BRAKE.

No. 824,718.

Specification of Letters Patent.

Patented July 8, 1906.

Application filed July 27, 1905. Serial No. 271,491.

To all whom it may concern:

Be it known that we, JAMES A. HICKS and FRANK H. HILL, citizens of the United States, residing at Atlanta, in the county of Fulton and State of Georgia, have invented new and useful Improvements in Fluid-Pressure Brakes, of which the following is a specification.

Our invention has relation to new and useful improvements in fluid-pressure brakes constructed for use in connection with railway-vehicles, and more especially to brakes of the general type stated embodying a main reservoir, a brake-cylinder, an auxiliary reservoir to receive air from the main reservoir and to discharge air under pressure into the brake-cylinder to actuate the brakes, the discharge of air being permitted and controlled by a valve device which depends for its operation upon a reduction of pressure in the brake-pipe which charges the auxiliary.

It is well known that with the fluid-pressure brakes now generally in use the efficiency of the brakes is often greatly impaired and speed and certainty in application reduced owing to the fact that under certain unavoidable conditions of operation the auxiliary and train-line pressures are reduced below the point necessary for the successful operation of the brakes. This may occur, for instance, when an emergency application of the brakes has just been made and the speed of the train and the grade are such that the application fails to hold the train or when the engineer's valve has been left on lap after making an application, so that the train-line has been bled and the auxiliary fails to charge or when the train-line pressure has been depleted on heavy inclines by continuous or repeated applications of the brakes.

It is our object, therefore, to provide means associated with a brake system of the character stated which will be operable by the engineer to set the brakes when ever the auxiliary or train-pipe pressure shall be so reduced as to be incapable of effecting the desired result, which means will be effective for operation whenever the auxiliary pressure falls below a degree of safety.

A further object is to provide means for the purposes stated which will be operable by the engineer for setting the brakes and when so operated will maintain the brakes set during the charging of the auxiliary through the triple and will be automatically

operated to release the brakes when the auxiliary becomes charged to fill running pressure or a pressure capable of effectively actuating the brakes.

The invention consists in associating with the braking apparatus a supplemental valve mechanism connected with the brake-cylinder and train-pipe and through which the air from the train-pipe may enter the brake-cylinder when said valve is open, the latter being maintained normally closed as long as there is working pressure in the auxiliary, but adapted to be opened by the admission of main-reservoir air to the train-pipe under conditions when the auxiliary pressure has been reduced below braking power.

We have fully and clearly illustrated our invention in the accompanying drawings, to be taken as a part of this specification, and wherein—

Figure 1 is a view in side elevation of a brake system including the improvements constituting our present invention. Fig. 2 is a view in side elevation of the attachment embodying our invention. Fig. 3 is a transverse section, and Fig. 4 is a horizontal section.

Referring to the drawings, 1 designates the main train-pipe which is connected at its forward end to the engineer's valve (not shown) in the usual manner and to the main reservoir. (Also not shown.) On each car leading from the brake-pipe 1 is a branch pipe 2, connected to the casing of a triple valve 3 and through which air from the brake-pipe enters said casing in charging the auxiliary reservoir 4, with which said triple valve is associated, the air passing to the auxiliary through the usual port.

5 designates the brake cylinder, which contains the usual brake-acting piston 6 and piston-rod 7, having the spring 8, tending normally to maintain said piston in release position. The brake-cylinder is connected to the triple valve by means of a pipe 9, through which air may pass from the auxiliary to said cylinder to actuate the brakes. This triple valve is shown as consisting of the well-known Westinghouse type, embodying a slide-valve controlled and operated in its movements by a piston, the latter being actuated by pressure in the train-pipe and said slide-valve having the usual ports for permitting the air to pass from the auxiliary to the brake-cylinder to exert its force upon the brake-piston.

and to exhaust the air from the brake-cylinder when the slide-valve is moved to the release and charging position. The triple also embodies an emergency-valve, by virtue of which the air may be passed from the brake-pipe directly to the brake-cylinder irrespective of the auxiliary and slide valve.

All of the parts thus generally set forth are of well-known form and construction, and it is therefore not deemed necessary to more specifically describe the same for the purposes of this specification.

We will now describe the improvements embodying our invention, which are to be employed in connection with the system above briefly described.

Before entering into a detailed description of the various elements and parts embodying our invention we might state that it is our purpose to actuate the brakes by admitting air from the main reservoir directly to the brake-cylinder and under main-reservoir pressure independently of the auxiliary and the triple valve, so that the brakes may be operated successfully while the triple valve is in its release position and the auxiliary charging.

Again referring to the drawings, 10 designates a valve-casing which is arranged between the auxiliary reservoir and the triple, being securely bolted in position, said casing being formed with a main passage 11, which constitutes a continuation of the passage in the triple, through which the air passes when the auxiliary is recharging and when the brakes are being applied, said passage 11 opening directly into the auxiliary reservoir. Also formed in this valve-casing 10 and shown running parallel with the passage 11 is a second passage 12, one end of which communicates with the pipe 9, leading to the brake-cylinder, the other end of said pipe connecting with the duct in the triple, to which said pipe is ordinarily connected.

From the construction so far described it will be seen that the operation of the triple is in no way changed, the latter being merely moved away from the head of the auxiliary a sufficient distance to permit the attachment to be placed in the position indicated.

Cast integral with the casing 10 is an extension 13, formed with a passage 14, which intersects the passage 12 and is formed at its inner end with a valve-seat 15, through which said passages open by way of an opening 16 into the chamber 17, the latter being of greater diameter than the passage 14. Also formed in the extension 13 and extending parallel with the passage 14 is a port or passage 18, which opens at its inner end into the passage 12, said passages 14 and 18 being connected by a chamber 19. This chamber is connected, by means of a nipple 20, with one end of a branch pipe 21, (see Fig. 1,) the other end of which is connected to the brake-

pipe at a point forward of the triple valve, so that air from the brake-pipe may pass directly into the chamber 19 without passing through the triple valve, the air on its way to the brake-cylinder traversing the chamber 19, port 18, and passage 12. In the port 18 is a check-valve 22 of any approved construction, which opens toward the passage 12 to permit the air to pass through the passage 12 to the brake-cylinder, but closes to prevent the air from flowing back through said port 18.

In the passage 11 at a point intermediate its ends is a chamber or pocket 23, formed in its bottom with an opening 24, surrounded by a valve-seat 24^a, said chamber 23 communicating with the chamber 17 by means of a duct 25, said duct opening into the last-mentioned chamber at approximately the rear end thereof. Slidably disposed in the passage 14 and extending across the passage 12 into the chamber 17 is a valve-rod 26 of smaller diameter than the said passages 14 and having mounted thereon a cylindrical valve-block 27, snugly fitting the interior of the passage 14 and adapted to be moved across the passage 12 to cut off the flow from the triple to the brake-cylinder. The valve-block is maintained in position on the valve-rod by means of a shoulder 28 on said rod and a packing-block 29, which closely fits the passage 14, and said rod carries at the end toward the chamber 19 a piston-head 30, which constitutes a valve to close the opening through the nipple 20. On the end of the rod 26 which projects into the chamber 17 is carried a piston 31, which is substantially twice the area of the piston-head 30, and it will be seen that when subjected to pressure the function of this piston will be to drive the piston-head 30 toward the seat on the nipple 20 to cut off direct pressure from the brake-pipe to the brake-cylinder and also to move the valve 27 from across the passage 12 to establish communication from the auxiliary to the brake-cylinder by way of the triple.

It will be apparent that when the auxiliary is charged to its full running capacity—say seventy pounds—and a substantial equilibrium of pressure is maintained between the brake-pipe and the auxiliary there will be the same pressure in the chamber 23 as in the auxiliary and that the air passes from said chamber through the duct 25 into the chamber 17 and exerts its force against the piston 31, which being twice the area of the piston 30 overcomes the pressure thereon from the branch pipe 21 and moves the valve-rod to bring the piston 30 against the nipple and carries the valve 27 from across the passage 12. It is therefore evident from the above that as long as a proper working pressure is maintained in the auxiliary the flow of air from the main reservoir at main-reservoir pressure is cut off and that the passage 13

12 is open to establish communication between the brake-cylinder and the auxiliary, so that the brakes are operated in the usual manner.

- 5 Means is provided whereby when the auxiliary pressure falls too low for the safe and efficient operation of the brakes the valves will be automatically shifted to close the passage through the passage 12 and open the 70 direct communication between the brake-pipe and the brake-cylinder, so that the brakes are efficiently set, and the operation thereof by auxiliary pressure is discontinued until the pressure in the auxiliary reaches the 75 proper degree for effective operation of the brakes. This means will now be described. Located in the chamber 23 is a reciprocatory valve 32, which co-operates with the valve-seat 24^a and is carried by a diaphragm 33, 80 20 which is at all times subjected to the air-pressure in the chamber 23, said diaphragm being operated when the proper auxiliary pressure is being maintained to keep the valve normally removed from its seat, so that communication is had between chamber 23 and the chamber 17, whereby the rear side of the piston 31 is at all times subjected to auxiliary pressure when the latter is at a safety braking power.
- 30 The diaphragm 33 rests upon a shoulder 34 formed in the casing 10 and is held in place by the lower end of a casing 35, threaded into the casing 10, as at 36, and in which is located an expansive governor-spring 37, 85 35 the lower end of which engages a block 38, carried by the upper side of the diaphragm. Threaded into the upper end of the casing is an adjusting-block 39, by means of which the tension of the spring may be regulated, 90 40 said block being accessible from the upper end of the casing, which is closed by a removable cap 40. This spring is set to exert a force of about fifty pounds, which is the lowest amount of pressure that should be 95 45 maintained in the chamber 17, and it will be seen that as soon as the auxiliary pressure falls below fifty pounds the spring 37 will immediately seat the valve 32 and cut off communication between the chamber 23 and the chamber 17. The auxiliary pressure against the piston 31 having been discontinued, the preponderating pressure from the brake-pipe on the piston-head 30 tends to move the valve-rod and valves 30 and 27 to 100 50 open direct communication between the main reservoir and the brake-cylinder. To permit this operation, we provide in the casing 10 a by-pass 41, connecting the chamber 23 and the chamber 42, in which chamber 55 55 operates a differential valve 43, adapted to open and close the by-pass and also to control an exhaust-opening 44 in the casing. The valve 43 is of the diaphragm type and consists of a disk which is adapted to coöperate with an annular seat 45, formed in said

chamber and above which is arranged an annulus 46, the under face of which is concaved and having an opening therethrough of less diameter than the area of the under side of the valve, which is exposed to the air-pressure, the valve and annulus being maintained in position by a bushing 47, threaded into position, as at 48, and engaging the upper side of the said annulus. The valve 43 receives the pressure on the entire surface exposed over the annular seat 45, the diameter of which is so proportioned that a pressure of twenty pounds in the auxiliary will keep the valve 43 seated against the fifty-pound pressure in the chamber 17, exerted on the lesser 80 area exposed to the under side of the valve 43. The annulus 46 is concaved on its under face to permit the disk of the diaphragm 43 to lift.

From the above it will be seen that as long as a proper degree of auxiliary pressure is maintained the air from the chamber 23 will exert its force upon the upper side of the valve 43 to keep the said valve seated; but as soon as the auxiliary pressure drops below 90 twenty pounds the fifty-pound pressure in the chamber 17 lifts the diaphragm-valve 43 from its seat and discharges the predominating pressure from the chamber 17 out through the passage 44, thus permitting piston 31 to 95 move when direct pressure is applied on piston 30 through the nipple 20 and the piston-head 30 is moved out of engagement with the nipple 20 and the valve 27 is moved across the passage 12 to cut off the flow of air from the auxiliary to the brake-cylinder. When the valve-rod is moved, as just described, the piston 31 forces the dead air against the under side of the valve 43, and the latter is raised from its seat, and the remaining air exhausts 100 from the chamber 17 through the opening 44. The valve 43 is permitted to move from its seat, owing to the difference in the areas of the upper and lower faces thereof, which are subjected to pressure.

By the operation just stated the brakes are set by direct pressure from the main reservoir whenever the auxiliary pressure falls below twenty pounds, the flow of air being cut off from the auxiliary to the brake-cylinder, so 115 that it is impossible for the engineer to use auxiliary air for braking power until the auxiliary reservoir has again been brought to the proper point for successfully operating the brakes. When the auxiliary pressure is again 120 sufficient to overcome the force of the spring 37, the valve 32 is raised from its seat, and the air at auxiliary pressure closes the valve 43 and flows into the chamber 17 and exerts its force on the piston 31 to move the valve-rod 125 to seat the piston-head 30 on the nipple 20 and to move the valve 27 so as to open the passage 12. The brakes can then be operated by the auxiliary pressure in the usual manner.

Having thus described our invention, what we claim as new, and desire to secure by Letters Patent, is—

1. In a fluid-pressure brake system, means for directing air from the main brake-pipe directly into the brake-cylinder independently of the triple valve, and automatic means controlled by auxiliary pressure for establishing and cutting off the flow of air from the brake-pipe to the brake-cylinder.
2. In a fluid-pressure brake system, the combination with the main reservoir, the triple valve, the auxiliary reservoir, the brake-cylinder and the main brake-pipe, of means for directing air from the main brake-pipe directly into the brake-cylinder and automatic means controlled by auxiliary pressure for establishing and cutting off the flow of air from the brake-pipe to the brake-cylinder, and means whereby communication from the auxiliary reservoir to the brake-cylinder is automatically discontinued during such time as the brake-pipe is in direct communication with the brake-cylinder.
3. In a fluid-pressure brake system, the combination of the main reservoir, the triple valve, the auxiliary reservoir, the brake-cylinder and the main brake-pipe, a passage to establish communication between the auxiliary reservoir and the brake-cylinder, and between the brake-pipe and the brake-cylinder, valve devices for controlling said passages whereby when one passage is opened the other is closed, and means controlled by the auxiliary pressure for automatically operating said valve devices and establish and cut off communication between the brake-pipe and the brake-cylinder.
4. In a fluid-pressure brake system, the combination with a main reservoir, the triple valve, the auxiliary reservoir, the brake-cylinder and the main brake-pipe, of means for directing air from the main brake-pipe directly into the brake-cylinder, means for establishing communication between the auxiliary and the brake-cylinder, means for controlling the flow of air into the brake-cylinder, whereby when it is permitted to flow directly from the brake-pipe the communication with the auxiliary is discontinued and means operable by the auxiliary pressure for actuating said controlling means.
5. In a fluid-pressure brake system, the combination with the main reservoir, the triple valve, the auxiliary reservoir, the brake-cylinder and the brake-pipe, a passage connecting the brake-pipe with the brake-cylinder independently of the triple valve, a passage connecting the auxiliary and the brake-cylinder, valves to control said passages whereby when one is opened the other is closed, and a piston to operate said valves, said piston being located in a chamber having communication with the auxiliary reservoir.
6. In a fluid-pressure brake system, the combination of the main reservoir, the triple valve, the auxiliary reservoir, the brake-cylinder and the brake-pipe, a passage to establish communication between the brake-pipe and the brake-cylinder, a passage connecting the auxiliary and the brake-cylinder, valves to control said passages whereby when one is opened the other is closed, a piston and piston-chamber for operating said valves, said chamber having communication with the auxiliary, and a governor-valve to control the communication between the auxiliary and said chamber.
7. In a fluid-pressure brake system, the combination of the main reservoir, the triple valve, the auxiliary reservoir, the brake-cylinder and the brake-pipe, a passage to establish communication between the brake-pipe and the brake-cylinder, a passage connecting the auxiliary and the brake-cylinder, valve devices for controlling said passages whereby when one is opened the other is closed, a rod upon which said valves are mounted, a piston-chamber, a piston connected to the valve and located in said chamber, said chamber having communication with the auxiliary, and a governor-valve for controlling the flow of air from the auxiliary to said chamber.
8. In a fluid-pressure brake system, the combination of the main reservoir, the triple valve, the auxiliary reservoir, the brake-cylinder and the brake-pipe, a passage to establish communication between the brake-pipe and the brake-cylinder, a passage connecting the auxiliary and the brake-cylinder, valve devices for controlling said passages whereby when one is opened the other is closed, a fluid-pressure device actuated by pressure from the auxiliary for operating said valves, a governor-valve to control communication between the auxiliary and said fluid-pressure device, and operating to cut off communication thereto when the auxiliary pressure falls below braking power.
9. In a fluid-pressure brake system, the combination of the main reservoir, the triple valve, the auxiliary reservoir, the brake-cylinder and the brake-pipe, a passage to establish communication between the brake-pipe and the brake-cylinder, a passage connecting the auxiliary and the brake-cylinder, valve devices for controlling said passages whereby when one is opened the other is closed, a piston-chamber having communication with the auxiliary, a piston in said chamber to actuate the valves, a governor-valve to control communication between said chamber and the auxiliary, and means to exhaust the air from the chamber at such times as the communication of the latter with the auxiliary is discontinued.
10. In a fluid-pressure brake system, the combination of the main reservoir, the triple valve, the auxiliary reservoir, the brake-cylinder and the brake-pipe, a passage to establish communication between the brake-pipe and the brake-cylinder, a passage connecting the auxiliary and the brake-cylinder, valve devices for controlling said passages whereby when one is opened the other is closed, a piston-chamber having communication with the auxiliary, a piston in said chamber to actuate the valves, a governor-valve to control communication between said chamber and the auxiliary, and means to exhaust the air from the chamber at such times as the communication of the latter with the auxiliary is discontinued.

- inder and the brake-pipe, a passage establishing communication between the brake-pipe and the brake-cylinder, a passage connecting the auxiliary and the brake-cylinder, valve devices for controlling said passages whereby when one is opened the other is closed, a fluid-pressure device actuated by pressure from the auxiliary to operate the valve devices, to cut off communication between the brake-pipe and the brake-cylinder, and open the connection between the auxiliary and the brake-cylinder, and a fluid-pressure device actuated by pressure from the main reservoir to move the valves to open communication between the brake-pipe and the brake-cylinder, to cut off the connection between the auxiliary and the brake-cylinder when the auxiliary pressure falls below a predetermined point.
11. In a fluid-pressure brake system, the combination with the main reservoir, the triple valve, the auxiliary reservoir, the brake-cylinder and the main brake-pipe, of means for directing air from the brake-pipe directly to the brake-cylinder, means for establishing communication between the auxiliary and the brake-cylinder, a movable member carrying differential pistons, the smaller of which is subjected to brake-pipe pressure, and the larger of which is subjected to auxiliary pressure, and a valve operated by said member to control the communication between the auxiliary and the brake-cylinder.
12. In a fluid-pressure brake system, the combination with the main reservoir, the triple valve, the auxiliary reservoir, the brake-cylinder and the main brake-pipe, of means for directing air from the brake-pipe directly to the brake-cylinder, means for establishing communication between the auxiliary and the brake-cylinder, a reciprocating rod carrying differential pistons, the smaller of which is subjected to brake-pipe pressure and the larger of which is subjected to auxiliary pressure, and a valve carried by said rod to control communication between the auxiliary and the brake-cylinder.
13. In a fluid-pressure brake system, the combination with the main reservoir, the triple valve, the auxiliary reservoir, the brake-cylinder and the main brake-pipe, of means for directing air from the brake-pipe directly to the brake-cylinder, means for establishing communication between the auxiliary and the brake-cylinder, a movable member carrying differential pistons, the smaller of which is subjected to brake-pipe pressure, and the larger of which is subjected to auxiliary pressure, a valve operated by said member to control the communication between the auxiliary and the brake-cylinder, and an automatically-operated valve to cut off the auxiliary pres-

sure on the larger piston when the pressure in the auxiliary falls below a predetermined point.

14. In a fluid-pressure brake system, the combination with the main reservoir, the triple valve, the auxiliary reservoir, the brake-cylinder and the brake-pipe, of a casing arranged between the triple valve and the auxiliary reservoir, and formed with passages to establish communication between the brake-pipe and the brake-cylinder, and the auxiliary reservoir and the brake-cylinder, the reciprocating member in the casing carrying differential pistons, the smaller of which is subjected to brake-pipe pressure and the larger of which is subjected to auxiliary pressure, a valve carried by the reciprocating member to control communication between the auxiliary and the brake-cylinder, and automatically-operated means to cut off the auxiliary pressure on the larger piston when the pressure in the auxiliary falls below a predetermined point.

15. In a fluid-pressure brake system, the combination with the main reservoir, the triple valve, the auxiliary reservoir, the brake-cylinder and the main brake-pipe, of a casing arranged between the triple valve and the auxiliary reservoir, passages to establish communication between the auxiliary reservoir and the brake-cylinder, and the brake-pipe and the brake-cylinder, a piston-chamber in said casing having an opening for auxiliary pressure, a movable member in the casing carrying differential pistons, the larger of which is arranged in said piston-chamber and the smaller of which is subjected to brake-pipe pressure, and a valve operated by said member to control the passage between the auxiliary and the brake-cylinder.

16. In a fluid-pressure brake system, the combination with the main reservoir, the triple valve, the auxiliary reservoir, the brake-cylinder and the main brake-pipe, of means for directing air from the brake-pipe directly to the brake-cylinder, means for establishing communication between the auxiliary and the brake-cylinder, a movable member, differential pistons to move said member, the smaller of which is subjected to brake-pipe pressure, and the larger of which is subjected to auxiliary pressure, and a valve operated by said member to control the communication between the auxiliary and the brake-cylinder.

In testimony whereof we have hereunto set our hands in presence of two subscribing witnesses.
